CLAIM

The ornamental design for a teapot, as shown and described.

DESCRIPTION

FIG. 1 is a top, front, right side perspective view of a teapot, showing my new design;

FIG. 2 is a right side elevational view, the left side elevational view being a mirror image thereof;

FIG. 3 is a top plan view thereof;

FIG. 4 is a front elevational view thereof;

FIG. 5 is a rear elevational view thereof;

FIG. 6 is a top, front, right elevational view showing a second embodiment of my new design;

FIG. 7 is a right side elevational view, the left side elevational view being a mirror image thereof;

FIG. 8 is a top plan view thereof;

FIG. 9 is a front elevational view thereof; and,

FIG. 10 is a rear elevational view thereof.

The base of the teapot or similar article is not ornamented.

FIG. 1.

FIG. 2.

FIG. 3.

FIG. 4.

FIG. 5.

FIG.6

FIG.7.

FIG.8.

FIG. 10.

FIG. 9.
